UNITED STATES PATENT OFFICE.

ALEXANDER THOMAS PORTER, OF ELIZABETH, NEW JERSEY.

METHOD OF PRODUCING COMBUSTIBLE VAPOR.

1,411,182.

Specification of Letters Patent. Patented Mar. 28, 1922.

Application filed May 5, 1917, Serial No. 166,639. Renewed October 7, 1919. Serial No. 329,144.

To all whom it may concern:

Be it known that I, ALEXANDER THOMAS PORTER, a citizen of the United States, residing in the city of Elizabeth, State of New Jersey, have invented a new and useful Method of Producing Combustible Vapor Having Approximately the Efficiency of the Liquid from Which It has been Formed, of which the following is a specification, reference being had therein to the accompanying drawings, forming a part thereof.

The object of the invention is to convert combustible liquids, temporarily, into that form of vapor commonly known as fog condition without chemically changing the liquid and by means which will cause the vapor to persist in that fog condition for a sufficient length of time so that it can be utilized for the various purposes to which it may be adapted.

When, by a correct method, the combustible liquid is so transformed by the direct action of a flame, with the minimum amount of combustion necessary, the liquid will not increase in temperature beyond its boiling point, nor decompose, and the product will be what is known in the art as a cool vapor.

I have found that various combustible liquids in this fog condition have valuable medicinal qualities, that they can be readily and safely taken into the respiratory organs of the human body and can also be used as a carrier for other substances employed in medical practice.

I have found that hydro-carbon oil when put into this fog condition in the manner stated can be used also and is well adapted for heating purposes and is of special value for internal combustion use.

The vapor produced by this process being capable of withstanding low temperature and high compression, this method would be a very valuable factor in the process of manufacturing dyes from tar and hydro-carbon products.

I have had previous experience with a process where, by the coordination of certain elements, hydro-carbon oil atomized by air, was passed into a flame of sufficient extent and intensity and caused to pass through the flame at high velocity, thereby producing an effect on the oil of vaporization only; however, by this method there was difficulty in the application of the product to some of the uses to which it was adapted; for in-

stance in applying the process to the operation of high speed engines the apparatus, (which is the physical expression of the process) when subjected to the severe condition of quickly changing from low to high speed, which is in effect an instantaneous change from minimum to maximum volume of product, and where the apparatus would be subjected to the influence of a widely variable suction of the engine, it was found difficult to maintain the coordinating elements of the invention in equilibrium. This difficulty I found was occasioned by a too intimate association of all of the finely divided (atomized) material with the flame and this in turn I found was occasioned by, and was incidental to, the too complete diffusion of the atomized air used in the process through the material under treatment; I sought to overcome this difficulty by localizing the combustion-supporting air with a view to localizing the flame, but found it impossible to do so for the reason that the ordinary methods of atomization employed required the use of an amount of air considerably in excess of the requirements of the process.

I found in attaining the object of this invention that atomization by an aeriform medium, as distinct from ordinary spraying, was essential for preparing the material for treatment, the flame action on the material requiring to be practically instantaneous and that atomization, as an important element of the invention, requires the atomizing medium be reduced to the least possible proportion; for whatever use the vapor may be intended, a primary object of the invention is to put the material intended for vapor-production into a condition of atomization where the flame action will cause instant vaporization without ignition.

If the product be intended for medical use it would be essential that air should be used as the atomizing medium, the use of which, for the reasons already shown, should be reduced to the least possible amount, while if the product were intended for other use, say internal combustion, and a non-combustion-supporting medium were used, such as, for instance, the exhaust from the engine, it would then, also, for obvious reasons be desirable to reduce as much as possible the relative quantity of the atomizing medium.

In the positive form of atomizers (those where the air is brought into direct contact

with the liquid before it reaches the atomizing nozzle and which are the most economical in air consumption) the air is brought into contact with the liquid at a distance 5 more or less remote from the atomizing nozzle, causing a stratification of the air and liquid before they reach the point of atomization, consequently the air cannot cause the full theoretic effect. I obviate this difficulty 10 by the form of atomizer shown in the drawings, by bringing the atomizing medium and liquid into positive contact at the point of atomization so that no stratification can occur. The liquid being brought over the 15 atomizing medium stream in a thin film is subjected to its full atomizing effect, thereby creating an essential element of the invention and constituting an important advance in the art to which the invention belongs. A 20 sufficient reduction in the percentage of air in the atomized spray enables me to create and localize a stratiform combustion zone in the spray so that the relative proportion of the spray which should be subjected to actual combustion and the amount that should be subjected to the effect (heat, etc.) of that combustion can be determined and fixed.

I have discovered that if a combustible 30 liquid such as hydro-carbon oil, for instance kerosene, be suitably prepared and enclosed in a tubuliform flame envelope with which it would be in direct contact, under correct conditions, the oil will under those circumstances be transformed, without chemical change, from a liquid to a condition of cool fog vapor irrespective of the ordinary demands made on the apparatus carrying out the process.

40 A further feature of the invention is the circumferential admission of a regulatable combustion-supporting atmosphere to the fine outward fringe of the atomized spray, which, when ignited, produces the tubuliform flame envelope of the intensity required to produce the cool fog vapor condition.

The combustion air being another and very important element of this invention, it is desirable that the manner of its application and how it should function and cooperate with the other elements should be clearly shown.

In the previous invention which I assisted in working out, the combustion air was admitted back of the atomizing nozzle, where, by the onrush of the atomized spray a partial vacuum was created, in other words, it was admitted at a point in the combustion chamber where there would be less than atmospheric pressure while the atomizer was in operation; thus providing a supply of combustion air by induction, and causing it to diffuse throughout the spray; the direction of flow being toward the point of atomization.

In this invention the combustion air is conveyed past the point where it can be influenced by the partial vacuum produced by the atomizer, and delivered at a point in the combustion chamber ahead of the atomizer 70 where the pressure would be greater than atmospheric pressure until a less than atmospheric pressure condition was caused by the suction of the engine, when, the direction of flow would not be to the centre but longitudinally of the combustion chamber, with little or no tendency to diffusion of the combustion air throughout the spray.

By the proper use and coordination of the foregoing elements I am enabled to utilize 80 another element which is of great importance.

The heavy fog vapor thus produced having a very low percentage of admixed air is highly resistant to flame action, consequently, by properly restricting the vapor at the discharge end of the combustion chamber, I cause it to bank up at that point, thereby extinguishing the flame envelope and thus determining the extent (length) of 90 the flame and consequently the time action of the flame on the material under treatment.

It is important that the spray should not meet any obstruction in its travel which 95 would cause it to condense, and by the foregoing arrangement I am able to remove all solid obstruction, such as screens, baffles, etc., in the path of travel of the atomized spray while it is being converted into the desired 100 vaporous condition.

A further feature of the invention is the removal of the ignition device from the path of the atomized spray, thereby removing it as an obstruction and placing it where it 105 will come in contact with the finer eddies from the spray fringe only, which, having a high admixture of air is in the form of an explosive mixture and will not, in consequence, foul the electrodes of the sparking device.

The ignition device is also set at such an angle to the flow of the material that no accumulation of oil can occur there to cause a short circuit.

115 My invention will be further explained with reference to the accompanying drawings, illustrating an apparatus for carrying the invention into effect; thereafter I shall point out the invention in claims.

120 Figure 1 is a vertical central section of an apparatus suitable for carrying out the process.

Figure 2 is an end view of head 1 looking in the direction of the arrows on lines 125 2-2.

Figure 3 is a sectional view of Figure 1 on line 3-3.

Figure 4 is a detailed perspective of nut 8.

Figure 5 is a sectional view of a modified form of the combustion chamber restriction 15.

Figure 6 is a sectional view of Figure 5 on lines 6—6.

The apparatus is made up of two general parts, the head 1 and the flame chamber 12 flanged and bolted together at 1^a; it is preferably operated in a vertical position, the 10 head 1 being the upper portion and the flame chamber 12 the lower. The head 1 carries the atomizer 21 and the means for delivering and controlling the combustion supporting air in the manner required. The 15 combustion chamber 12 carries the ignition device, also the restricting wall 15 which regulates the flow of the vapor from the apparatus at the opening 15^a.

Inlet 4 in head 1 is adapted to carry a 20 needle valve (not shown) or other suitable device for supplying and controlling the flow of the combustible liquid which, under pressure, is there admitted to the apparatus and flows thence to annular chamber 3. Inlet 6 is adapted to carry a needle valve (not 25 shown) or other suitable device to receive and control the flow of the atomizing medium which is there admitted and flows thence, under pressure, to passage 5, where 30 it and the combustible liquid come in physical contact in a direct line with and close to the opening 2^a, in atomizing nozzle 2. In this way when the apparatus is put in operation by opening valves at 4 and 6 35 the combustible liquid and the atomizing medium being under pressure, produce at 2^a an atomized spray of the fineness required with the least possible amount of the atomizing medium, the object of the invention being to reduce the combustible liquid to the required degree of fineness while keeping its degree of combustibility as low as possible. It is well known that combustible 40 liquid such as kerosene or fuel oil are difficult of ignition except when used in connection with a saturated wick, or finely divided with a considerable admixture of air. For this reason the amount of air used in 45 atomizing will determine, for the purpose of the process, the degree of combustibility of the liquid and if a dead gas, such as the exhaust from an internal combustion engine is used as the atomizing medium, the atomized spray will be at its highest point of 50 resistance to combustibility. Thus it will be seen that to cause the atomized spray to ignite and to sustain combustion it is necessary to admit to the chamber 12 a combustion supporting atmosphere, and only where 55 that atmosphere becomes intimately associated or mixed with the spray will combustion prevail. For this reason provision is made for the admission of combustion supporting air which is brought into contact 60 with the spray in such a manner and to a

sufficient degree to cause combustion of part of the spray sufficient to cause the remainder of the spray to increase in temperature to its boiling or vaporizing point. For this purpose air is admitted by some suitable 70 controlling device at opening 9 in cap 9^a. If the apparatus is attached to a vacuum pump or internal combustion engine the combustion air will flow in at atmospheric pressure, otherwise it may be necessary to 75 put it under independent pressure.

The combustion air admitted at 9 spreads in chamber 10 and passes uniformly through passages 11 into the annular space 8' created by flange 8^a of nut 8 fitting snugly in the 80 entrance to chamber 12, where the air again spreads and equalizes and passes through opening 14 in flange 8^a of nut 8 and is delivered by flange 7 in a uniform stream circumferentially to chamber 12. As hereinbefore explained, if the flange 7 is extended to a point in chamber 12 where the combustion air is delivered free from the influence of the spray at the point of the atomizing nozzle it will take the shortest course 85 and path of least resistance and will travel circumferentially of the chamber 12 to the outlet 15^a.

In carrying out the process the principal question to be determined is the amount of 90 combustion necessary to vaporize the material not undergoing combustion. The amount of combustion is determined by two factors; one the intensity of the flame, the other the depth to which the flame action 95 penetrates the atomized spray. Both of these can be predetermined.

The intensity of the flame is determined by the amount of air admitted through the 100 controlling device at 9. The depth to which the combustion will penetrate the spray will depend on the length of flange 7, the shorter flange 7 is made the more will the combustion air be brought under the influence of 105 the partial vacuum produced at the atomizing nozzle where, the direction of flow is toward the center of the chamber, consequently the more the combustion air is brought under that influence, the deeper will 110 it penetrate the spray and, naturally, the flame will follow, so, obviously, by regulating the amount of combustion air, and its point of delivery to the combustion chamber, the exact amount of combustion which 115 will take place can be determined.

As the atomized spray passes on through 120 combustion chamber 12 surrounded by its combustion supporting atmosphere the finer outer particules of the spray mixed with the combustion air come in contact with the spark created by the electrode 17 of sparking device 16 and immediately a tubuliform 125 flame is produced, through which the vapor-producing part of the spray travels until it is vaporized. The contracting wall 15 at 130

the outlet of the combustion chamber causes the cool, heavy vapor with its low percentage of air to extinguish the flame at that point, when the vapor may be collected for use. Should greater restriction to the flow of the vapor at 15^a be required than that shown it can be obtained by substituting the device shown in Figure 5 for the restricting wall 15.

10 Figure 5 is a modification showing greater restriction to the flow of the vapor than that shown on Fig. 1 at 15, it consists of two caps 22 and 23, the inner cap 23 having two slots 25, on opposite sides; the outer cap 22 has 15 similar slots 24 arranged as shown in Figures 5 and 6 so that the vapor flows through slots 25 and passes between caps 22 and 23 and has its outlet at slots 24 in outer cap. This arrangement is intended for high speed 20 engines where the suction is variable, sudden and severe.

Should the apparatus, for any reason, fail to function properly causing oil to flow through, unvaporized, a drip opening 26 25 (Fig. 5) is provided which can be connected with any suitable receptacle.

It is obvious that various modifications 30 may be made in the method above particularly described and also in the construction for carrying out such method shown in the drawings and above particularly described within the principle and scope of my invention.

In this process so delicate yet precise in 35 its operation and where the product can be put to so many uses, an apparatus to give it full expression must have great flexibility. I feel that I have not only accomplished this purpose, but also reached the other great desideratum of mechanically expressing the 40 process by an extremely simple device where the elements operate and coordinate in a natural manner without artificial expedients.

45 I do not confine myself to the method of atomizing shown in the drawings, but show it as a means whereby one of the essential elements can be expressed; a fundamental feature of the invention being the discovery 50 that it was necessary to put the material under treatment into a condition so that it would be highly susceptible to flame action but highly resistant (comparatively) to combustibility and the working out of a method to give effect to that principle:

I claim:

1. The method of producing a cool fog vapor from a combustible liquid, which consists in providing a supply of combustible 60 liquid, atomizing the liquid, admitting a combustion supporting medium in the form of a tubular film to the atomized liquid, igniting the outer portion of the atomized liquid to form a tubular flame whereby the liquid to form a tubular flame whereby the 65 unignited portion of the combustible liquid

is converted into a cool fog vapor, and discontinuing combustion when the liquid has been transformed to a cool fog vapor.

2. The method of producing a cool fog vapor from a combustible liquid, which consists in providing a supply of combustible liquid, introducing into the combustible liquid an atomizing medium, whereby the liquid is transformed into an atomized spray, admitting a combustion supporting medium 70 in the form of a tubular film to the atomized spray, igniting only the outer portion of the atomized liquid to form a tubular flame whereby the unignited portion of the combustible liquid is converted into a cool fog 75 vapor, and discontinuing combustion when the liquid has been transformed to a cool fog vapor.

3. The method of producing a cool fog vapor from a combustible liquid, which consists in providing a supply of combustible liquid, atomizing the liquid, admitting a tubular film of combustion supporting medium to the atomized liquid, igniting the outer portion of the atomized liquid to form a 80 tubular flame, combustion being supported by the combustion supporting medium, causing unignited atomized liquid to travel within the tubular flame until the liquid has been 85 transformed to a cool fog vapor, and discontinuing combustion when the liquid has been 90 transformed to a cool fog vapor.

4. The method of producing a cool fog vapor from a combustible liquid, which consists in providing a supply of combustible 100 liquid, atomizing the liquid, admitting a regulatable supply of combustion supporting medium in the form of a tubular film to the atomized liquid, igniting the outer portion of the atomized liquid to form a tubular flame whereby the unignited portion of the combustible liquid is converted into a cool fog vapor, and discontinuing combustion 105 when the liquid has been transformed to a cool fog vapor.

5. The method of producing a cool fog vapor from a combustible liquid, which consists in providing a supply of combustible liquid, atomizing the liquid, admitting a tubular film of combustion supporting medium 110 to the atomized liquid, igniting the outer portion of the atomized liquid to form a tubular flame, causing the unignited portion of the liquid to travel within the tubular flame and in contact therewith whereby the unignited atomized liquid is converted into a fog vapor, and discontinuing combustion 115 when the liquid has been transformed to a cool fog vapor.

6. The method of producing a cool fog vapor from a combustible liquid, which consists in providing a supply of combustible liquid, introducing into the liquid an admixture of air insufficient to support combustion 125 of the liquid, the liquid being transformed 130

into an atomized spray by the admixture of air, admitting a combustion supporting medium circumferentially to the atomized spray, igniting that portion of the atomized spray, 5 igniting only the outer portion of the liquid to which the combustion supporting medium has been admitted to produce a tubular form flame whereby the liquid is converted into a cool fog vapor, and discontinuing combustion when the liquid has been transformed to a cool fog vapor.

10 7. The process of producing a cool fog vapor from combustible liquid, which consists in producing a substantially continuous supply of combustible liquid, atomizing the

supply of liquid to form a substantially continuous flow of finely subdivided combustible liquid in the form of a spray, subjecting the spray to the direct action of a flame produced by igniting only the outer portion of the finely divided liquid whereby the 20 liquid is converted into a fog vapor, and discontinuing combustion when the liquid has been transformed to a cool fog vapor.
